UNITED STATES PATENT OFFICE.

THOMAS F. WHELAN, OF EAST ORANGE, NEW JERSEY, ASSIGNOR TO SAVODAY RACK COMPANY, OF ST. LOUIS, MISSOURI, A CORPORATION OF MISSOURI.

METHOD OF TREATING SHOES.

1,157,480.

Specification of Letters Patent.

Patented Oct. 19, 1915.

Original application filed December 17, 1909, Serial No. 533,533. Divided and this application filed March 15, 1915. Serial No. 14,415.

To all whom it may concern:

Be it known that I, THOMAS F. WHELAN, a citizen of the United States, residing at East Orange, in the county of Essex and State of New Jersey, have invented certain Improvements in Methods of Treating Shoes, of which the following description, in connection with the accompanying drawings, is a specification, like reference characters on the drawings indicating like parts in the several figures.

My invention consists in a novel method of treating shoes, and particularly enameled leather shoes, and this application is a division of my application Serial No. 533,533, filed Dec. 17, 1909, for a method of drying shoes.

In the manufacture of shoes, it is customary to use stiffening paste or gum between the lining materials of the toe of a shoe in forming the box or stiffened toe of the shoe and to put the shoe aside after lasting for a considerable length of time to permit the paste or gum to dry. When shoes are dried in the air, the operation, if atmospheric conditions are unfavorable, may take several days, and in the case of enamel or "patent" leather shoes, the alternation of cold and warmth, dryness and dampness causes irregular expansion and contraction in the material of which the toes are composed and thus checks or cracks the enamel, which is glazed on patent leather at a temperature of 200° to 300° F. Patent leather enamel is also liable to be cracked or scratched in the manufacturing operations, for instance, when the leather is bent and pulled sharply by the shaping devices during the lasting operation. It has been proposed to repair such damage to patent leather tips by buffing out the cracks in the injured surface, applying a thin coat of liquid enamel or "filler" on a cloth and polishing it as it dries, repeating the operation until a coat of the required thickness has been built up, after which the tips are lacquered or "flowed." This method is open to numerous objections, the most serious being that it is slow and expensive.

The object of my invention is to provide an improved process of repairing such damage to patent leather.

The distinctive characteristic of my novel method is baking or vulcanizing the coating

of enamel used in repairing patent leather 55 shoes.

In the manner of practising my novel process herein illustrated, heat is applied at progressively varying temperatures over the surface of a patent leather shoe, a portion of which is undergoing repair, whereby damage due to a too sharp temperature gradient is avoided.

In the drawings, which show a simple apparatus for practising my novel process:— 65 Figure 1 is an end elevation of a simple form of apparatus used in carrying out my improved method; Fig. 2 is a cross section taken on the line 2—2 of Fig. 3; Fig. 3 is a vertical section taken on the line 3—3 of 70 Fig. 1; and Fig. 4 is a vertical section taken on the line 4—4 of Fig. 1.

An elongated housing 1 is preferably constructed of sheet metal, and provided at its rear side with a depending portion 2, in 75 which the heating means is located. The housing has end walls 3 and, if desired, partitions 4 may be located at suitable points throughout the length of the housing.

The front wall 5 of the housing is preferably formed of a sheet of asbestos or similar material in which are formed openings 6, into which the toes of the shoes are to be inserted. These openings 6 substantially conform in shape to the cross-sectional outline of the toe portion of a shoe. Ears 7 depend from the end portions of the housing, and carry set screws 8, which are adapted to bear against the ends of the shelves of an ordinary shoe rack. Thus the shoe racks now in general use in shoe factories may be equipped to practise my novel process.

The entire interior surface of the housing is preferably lined with asbestos 9, or other non-conductor of heat, in order to prevent 90 wasteful radiation of heat from the housing. I prefer to curve the rear portion of the top of the housing and the upper portion of the rear wall thereof in order to do away with dead air space, and such curvature of the 100 rear portions of the housing also tends to reflect the heat generated by the heater located in the depending portion 2 directly against the toes of the shoes in the openings 6, and to direct the current of heated air 105 generated by the heater around and over the toes of the shoes.

The heating means employed is preferably

an electric heating coil 10^a located in the depending portion 2 of the housing. The generation of the heat is regulated by a suitable rheostat 10.

5 In order to provide for circulation of air through the housing, openings 11 are formed by nipples 12^a on the end walls 3 adjacent the ends of the heating coil. Caps 12^b are screwed on the nipples 12^a and dampers 12 are rotatably mounted on the caps 12^b to control the openings 11.

Where shoes are to be treated by my novel process, the housings are clamped on the shelves of the shoe racks, and the heating 15 coil is energized and regulated by the rheostat so that the proper temperature may be obtained in the housing. The toes of the shoes are buffed according to the usual practice in repairing patent leather shoes, to 20 form a proper surface for reënameled, coated with liquid enamel, and inserted into the openings 6 and baked. The housing is comparatively small and the openings 6 are of such size as to receive only the toe portions 25 of the shoes, and thus it is not necessary to generate a large amount of heat. In this baking operation a lower temperature is used for a shorter time than is the practice where the toes are merely being 30 dried to set the box, as shown and described in my parent application No. 533,533.

It is desirable to protect the shoes from 35 too direct application of heat in order to avoid damaging the leather, and I have found it advantageous to convey the heat to the shoes by means of a circulating current of heated air. In the apparatus shown in the drawings these objects are accomplished by locating the heating medium in front of 40 the toes of the shoes in a depression in the floor of the heating chamber and by curving the back wall of the chamber to deflect the ascending current of heated air over and around the toes of the shoes and to reflect 45 radiated heat in the same manner. I secure the protection of the bottom of the shoe from direct heat by the asbestos covering of the floor of the chamber. I desire also to avoid checking or cracking uninjured portions 50 of the leather, near those portions being treated, by sharp variations in the temperature imparted to the leather. This object is accomplished in the apparatus shown, by making the openings 6 loose 55 fitting, it having been found in practice that air from outside the receptacle will enter between the bottoms of the shoes and the lower walls of the openings and form an air cushion, and that the heated air 60 escapes between the upper portions of said openings and the shoes after passing over and around the toes of the shoes, and, mingling gradually with the outer air, becomes 65 gradually reduced in temperature as it passes from the openings 6 over the leather

toward the heels of the shoes. This insures a much more uniform temperature gradient in the leather adjoining the tips, avoids damage due to rapid and irregular variations in temperature, and adds further protection to the shoe bottom from the direct heat. The escaping current of hot air also tends to shrink out wrinkles in the vamps.

70 While I have shown a simple form of apparatus for practising my improved process, it will be understood that other apparatus may be employed, it being essential only that a proper temperature be applied 75 directly to the leather.

I do not claim herein the novel apparatus 80 disclosed since I have claimed it in my application, No. 578,930, filed Aug. 25, 1910, which is likewise a division of my application, No. 533,533, filed Dec. 17, 1909. Nor do I claim herein the disclosed novel method 85 of drying shoes, since I have claimed it in the above mentioned parent application No. 533,533.

90 What I claim as new and desire to secure by United States Letters Patent is:—

1. That improvement in processes of refinishing patent leather shoes which comprises subjecting patent leather portions of the shoes to heated air at a sufficient temperature to bake the enamel, said air being confined within a substantially closed compartment around the said patent leather portions.

2. That improvement in processes of refinishing patent leather shoes which comprises confining patent leather portions of the shoes in a chamber while the remaining portions of the shoe upper project therefrom, and subjecting the portions in the chamber to a current of heated air which 100 moves over and downwardly upon said patent leather portions before passing out of said chamber.

3. That improvement in processes of refinishing patent leather shoes which comprises confining patent leather portions of the shoes in a chamber while other portions project through openings therein, and subjecting the portions in the chamber to a current of heated air which moves over and 110 downwardly upon said patent leather portions and then passes out of said chamber through the said openings.

4. That improvement in processes of repairing damaged patent leather shoes which comprises applying enamel to the damaged patent leather portions of the shoes, confining such portions in a chamber and subjecting them to a current of heated air at a temperature sufficiently high to bake the 120 enamel.

5. That improvement in processes of repairing patent leather shoes which comprises applying enamel to the damaged patent leather portions, and then subjecting 130

the damaged portions to a current of heated air, the remaining portions of the shoe being substantially protected from the circulating heated air during this operation.

5 6. That improvement in processes of repairing a portion of a patent leather shoe which comprises reënameled said portion, subjecting it to air at a temperature sufficient to bake the enamel and protecting 10 the remainder of the shoe from said air in varying degree.

7. That improvement in processes of repairing a patent leather shoe which comprises reënameled the damaged portion, 15 passing over it a current of air at a temperature sufficient to bake the enamel, and conducting said air away from said damaged portion and over adjacent portions of the shoe at a progressively decreasing 20 temperature.

23 8. That improvement in processes of repairing a patent leather shoe which comprises reënameled the damaged portion, in-

serting it into a chamber through a loosely fitting aperture in a wall thereof, and providing a current of heated air in said chamber which circulates around said damaged portion, then passes out of the casing through said aperture, and treats portions of the shoe outside said chamber at a progressively decreasing temperature. 25 30

9. The method of drying and hardening solutions applied to shoes which comprises the disposition of the part carrying the solution within a heated receptacle, simultaneously disposing the portions of the shoe upper not treated with the solution without said receptacle, and restricting the action of the heat to the part within the receptacle. 35

10 In testimony whereof I have signed my name to this specification in the presence 40 of two subscribing witnesses.

THOMAS F. WHELAN.
